ELECTRIC LAMP.

Application filed July 22, 1924. Serial No 727,531.

My invention relates to electric lamps, and particularly to the base of the lamp. The object of my invention is to provide a lamp base with self-contained means which, 5 upon the removal of the lamp from a standard socket, operates to disable the lamp and render it unfit for further service.

My invention is susceptible of embodiment in various forms, only some of which are 10 shown in the accompanying drawings, in which

Fig. 1 is a broken section through a standard lamp socket into which is inserted a lamp base embodying my invention in one 15 form;

Fig. 2 is a section on the line 2—2, Fig. 1;

Fig. 3 is a dropped section of the base and bulb illustrating the assembly of the parts;

20 Fig. 4 is a section on the line 4—4, Fig. 3;

Fig. 5 is a side elevation of the lamp base detached;

Fig. 6 is a perspective of the lever blank detached;

25 Fig. 7 is a broken elevation of a lamp base in which my invention is embodied in modified form;

Fig. 8 is a section on the line 8—8, Fig. 7;

30 Fig. 9 is a perspective of the modified lever used in the construction shown in Fig. 7;

Fig. 10 is a dropped perspective of the insulating washers used in both of the constructions above referred to;

35 Fig. 11 is a broken section through a lamp base in which my invention is embodied in another modified form, the sub-figures A and B being broken elevations of opposite sides of the base; and

40 Fig. 12 is a section on the line 12—12, Fig. 11.

Various devices and attachments have been proposed for preventing theft of lamps installed in factories, hotels, trains, etc. For 45 the most part these devices have involved special socket constructions, and are not available for use in standard sockets. It has also been proposed to provide the lamp base with a swivelling shell contact which 50 prevents removal of the lamp without breakage of the bulb, but devices of this character have not proved consistently theft-proof and may be easily removed in most instances. Other constructions have been proposed which require a longitudinal dis-

placement of the bulb with respect to the shell contact of the base in order to secure its removal; incidentally the lead wire connection to the filament is ruptured, thus placing the lamp out of commission. Both 60 of these double shell constructions add materially to the cost of manufacture of the lamp, and are in any event trappy and uncertain in their operation. It has also been suggested to apply a center contact of special construction to the lamp base—or to apply a detachable washer to the center contact, with the object in both instances, of wrenching off the center contact and destroying the utility of the lamp in the act of 65 removal from the socket. This type of construction is bad electrically as it leaves metal elements in the socket, and these must be removed before another lamp can be inserted. Not only is danger of short circuit of 70 the socket introduced, but also danger of shock to the attendant who attempts to get the metal parts out of the socket.

My invention provides means self-contained in the lamp base, which operate automatically, on the unscrewing of the lamp, to render the lamp unfit for further use. These means are removed with the lamp and leave the socket clean and ready for the reception of another lamp. The lamps containing my invention are not materially increased in cost. The operation of the device is certain and involves no danger to the attendant.

Referring to the embodiment of my invention in Figs. 1 to 6, I have shown a standard lamp socket having an insulating body 15 on which are mounted a center contact 16 and screw shell 17 housed within the usual casing 18 and insulating lining 19. 90 The lamp comprises the standard bulb 20 within which is the lamp filament 21 supported on the glass cane 22 fused to the hollow stem 23. Also fused to the head of the stem is the exhaust tube 24 which extends beyond the open end of the stem 23 and, after evacuation of the bulb, is sealed by fusion, at the nib 25. The lead wire 26 sealed in the head of the stem 23, passes out between the stem and tube and is carried to the screw shell contact 27 of the lamp base, to which it is soldered. The other lead wire 28, also sealed in the head of the stem 23, passes out between the stem and tube to the center contact 29 of the lamp base to 105 110

which it is also soldered. The center and shell contacts are rigidly united by a button 30 of insulating material, such as glass. The bulb is seated against the open end of the screw shell 27 and secured in position by cement 31. These features are standard in modern lamp construction.

The mechanism which operates to destroy the utility of the lamp on its removal is arranged within the chamber afforded within the screw shell contact 27 and between the button 30 and the base of the stem 23 of the bulb 20. To keep this chamber open, to limit the quantity of cement used, and to prevent the cement from coming into contact with the operating parts, I provide a circular washer 32 of paper, fiber or the like, which is forced into the open end of the screw shell to approximately the plane of the base of the stem element 23 of the bulb when the latter is seated against the screw shell. While the base of the stem may not actually seat against the washer, it approaches sufficiently close to confine the cement in the area between the margin of the screw shell, the washer and the base of the stem, ample cement being present to effect a rigid connection while at the same time the chamber beyond the washer is maintained clean and free. Space for the rupturing mechanism hereinafter described is thus afforded.

Within the chamber beyond the washer 32, I provide rupturing mechanism of any suitable construction. A practical device for this purpose comprises a lever 33 (Fig. 2) anchored at one end to the nib end of the exhaust tube 24 and slightly projecting at its opposite end through a circumferential slot 34 formed in the screw shell 27. Any suitable engagement with the tube 24 may be effected. I have shown the anchorage end 35 of the lever provided with an opening X of considerably greater diameter than that of the tube 24, and thus accommodating the lever end to the nib end 25 of the tube with considerable latitude to take care of variations incident to manufacture. A gob 36 of cement rigidly unites the tube and lever, while this cement is prevented from uniting the parts to the base of the stem 23 by a washer 37 of paper, or the like, which is slipped over the nib end of the tube 24.

The projecting outer end of the lever is bevelled to a point 38, the bevelled margin 39 of the point being the leading edge of the lever when the lamp base is screwed into the socket shell 17. In the following edge of the lever, slightly inward from its point, is formed a notch 40 which engages the screw shell 27, and by which the lever is held against inward displacement while the lamp is being screwed into the socket. Preferably the shell is offset inward in the area of the circumferential slot 34. This permits the

location of the notch 40 a sufficient distance inward from the pointed end 38 of the lever 33 to insure ample mechanical strength in the pointed end of the lever—an effect not so readily attained if the notch 40 is located closer to the point. Instead of indenting the shell throughout the length of the slot the same result could be secured by offsetting inward a supporting tongue at the following end of the slot which would engage the notch 40. Such a construction, however, does not afford as great strength as that shown, and it will be realized that ample support is necessary in order to prevent the inward displacement of the lever during the insertion of the lamp base in the socket, and to prevent rupturing strain on the tube 24.

I have described the lever in the form which it assumes in the commercial lamp. During the course of manufacture it is preferably in the form of the blank shown in Fig. 6, and comprises two legs 41 and 42 projecting in opposite directions from the anchorage 35. The leg 41 is weakened at 43 to afford a point of breakage within the chamber. The leg 42 is weakened at 44 for the same purpose, and for the further purpose of forming, with the lever 33, a spring fork. It will be noted that the screw shell 27 of the base is provided, opposite the slot 34, with an aperture 45. To assemble the lever in proper position with respect to the shell during the course of manufacture of the base, it is only necessary to pass it inward through the slot (the leg 41 leading) until the leg 41 projects through the aperture 45 in the opposite side of the shell. The spacing of the leg 42 from the lever 33 is such that the overall width of the fork adjacent its outer end, slightly exceeds the length of the chord of the slot 34. Consequently a slight effort is necessary to push the lever home—that is, until the notch 40 engages the edge of the shell at the following end of the slot 34. The spring of the leg 42 permits this, and also serves to snap and hold the lever notch 40 in engagement with the edge of the shell (Fig. 4). The lever blank may be permitted to remain in this condition (Figs. 3 and 4) until the remaining assembly operations are all completed, whereupon the projecting end of the leg 41 may be readily broken off by a slight twisting motion while the leg 42 may be broken off by bending it (see dotted line Fig. 4) toward the lever 33, thus leaving the latter in the finished article in the form shown in Fig. 2.

The operation of the device will be readily understood. While the lamp base is screwed into the socket shell 17, the bevelled face 39 of the projecting end of the lever leads, and offers no material opposition to the insertion of the lamp base in the screw shell. During this operation the lever 33 is supported

against inward displacement by the engagement of its notch 40 with the shell 27 at the following end of the slot 34. No strain is therefore placed upon the exhaust tube 24.

- 5 When the lamp is reversely rotated, however, to remove it from the socket, the pointed nose 38 of the lever digs into the shell 17 of the socket and restrains the lever against movement with the lamp base. The lever is therefore held stationary while the base turns (the arcuate slot 34 accommodating the lever during this period) with the result that the exhaust tube 24 is broken and the lamp is thus disabled. In this condition the filament 21 at 15 once burns out when current is again applied. As soon as the tube breaks, the support for the inner end of the lever 33 is removed, and the lever is displaced inward by the socket shell into the chamber of the lamp base, thus 20 permitting the latter to be freely unscrewed from the socket, carrying the broken parts with it. The socket is thus cleared and is in condition to receive a fresh lamp.

It will of course be understood that the 25 invention is equally applicable to gas-filled lamps, which in the course of manufacture are first evacuated through the exhaust tube 24 and then filled with an inert gas before the nib 25 is sealed off. Upon breakage of 30 the tube by the present device, the escape of the gas from and the entrance of air into the bulb render the latter unfit for further use, just as effectively as the destruction of the vacuum of a vacuum lamp.

35 In both cases the bulb remains intact, since rupture of the tube 25 does not affect the bulb. Consequently the lamp may be unscrewed from the socket by grasping the bulb and such dangers as are incident to a removal of the base from the socket after the bulb is broken, are entirely eliminated. It is again pointed out that after it has performed its function, the rupturing lever moves to position within the base and is thus 45 withdrawn with the latter as the lamp is unscrewed.

The same result can be accomplished in other ways—for example as shown in Figs. 7, 8 and 9. Here the lever 46 is extended 50 across the chamber of the base and is provided at one end with a bevelled point 47 which projects through the circumferential slot 48 in the shell 27, while its opposite end is provided with bosses 49 which are loosely 55 accommodated in holes 50 in lugs 51 struck inward from the opposite side of the shell. The intermediate portion 52 of the lever is enlarged and pierced to accommodate a close fitting ring washer 53 of insulating material, 60 through which the nib end of the exhaust tube 24 passes. In assembled position the projecting end of the lever lies at the following end of the slot 48, while it is supported at its opposite end against displacement, by 65 one of the lugs 49. The lamp base may

therefore be screwed home in the socket without danger of injury to the exhaust tube. When the lamp is reversely rotated, however, the lever point 47 digs into the socket shell, and the lever swings through the 70 slot 48, thus rupturing the exhaust tube 24.

Upon further unscrewing of the lamp base in the socket, the bevelled face of the lever point is engaged by the opposite end of the slot 48 and cammed inward sufficiently to 75 withdraw its point from detaining engagement with the screw shell and permitting the lamp to be freely unscrewed from the socket.

It will be obvious that if desired an insulating bushing such as 53 may be inserted 80 in the anchorage aperture X of the lever 33 first described, to prevent any possible contact between the metal of the lever and the center contact lead 28. In most cases, however, the gob of cement 36 suffices for this 85 purpose, particularly if the lead be given a turn around the nib 25 as shown.

Instead of disabling the lamp by rupturing the exhaust tube, the lever may be used to rupture one of the filament lead wires, for 90 example, as shown in Figs. 11 and 12. In this modification, a rigid bridge member 54 is mounted in the lamp base and provided with a central steel bushing 55 insulated by a ring washer 56. A juxtaposed swinging 95 lever 57 is similarly provided with a steel bushing 58 insulated by a ring washer 59. When the bushings 55 and 58 are in register they afford a closely fitting passage for the lead wire 28, and in this position the projecting pointed end 60 of the lever lies at the following end of the circumferential slot 61 in the base shell. When the lamp is turned into the socket, no displacement of the lever 57 with respect to the bridge 54 occurs. On 100 reverse rotation, however, the bridge 54 turns with the shell, while the lever 57 is held stationary, and the lead wire 28 is sheared a7 the bushings 55 and 58 move out of register, thus rendering the lamp unfit for further 110 duty. Further outward rotation of the base cams the lever inward, as above described, and permits the lamp to be freely removed from the socket.

The bridge 54 and lever 57 may be mounted 115 in the base in any suitable fashion. For example, at one end both may be notched to straddle a shouldered web 62 inwardly offset from the shell. At an opposite point the shell is provided with a shouldered tongue 120 63 which the end of the bridge straddles, while the projecting end of the lever rests on the tongue and swings through the adjacent slot 64. Various other ways of accomplishing the result will readily occur to those 125 dealing with the construction. It is obvious furthermore, that the projecting ends of the levers 46 and 57 may be provided (see dotted lines) with notches such as 40 (Fig. 6) 130 which engage the following end of the slot

through which they swing, in order to afford additional support against inward displacement incident to end pressure thereon by the screw shell of the socket while the 5 lamp base is being inserted. Inasmuch as the lever in each case is supported at its opposite end by the shell contact of the lamp base, this notch is not so necessary as in the construction first described.

10 In all of the constructions, the mere act of removal of the lamp in ordinary fashion, causes the operation of the self-contained means which renders the lamp unfit for further service. This underlying thought may 15 be embodied in other specific structures without departing from what I claim as my invention.

I claim—

1. An electric lamp having a bulb, a base 20 rigidly joined thereto and comprising only a single screw shell, a lamp element projecting into the base below the joint between the bulb and base, and means arranged within said base and operative, on relative angular 25 displacement with respect to the base, to disorganize said lamp element within the base and thus disable the lamp.

2. An electric lamp having a bulb, a base 30 rigidly joined thereto and comprising only a single screw shell, a lamp element projecting into the base below the joint between the bulb and base, and means arranged within 35 said base, but projecting therefrom for external actuating engagement, and operative on relative angular displacement with respect to the base, to disorganize said lamp element within the base and thus disable the lamp.

3. An electric lamp having a screw shell 40 base for engagement with the screw shell of a cooperating socket, a bulb having a rigid joint with said base and a lamp element extending below said joint into the base, in combination with means carried 45 within said lamp base screw shell to engage the socket shell and serving to automatically disorganize said lamp element within the base and thus disable the lamp during its reverse rotation for withdrawal from the 50 socket.

4. An electric lamp having a screw shell base for engagement with the screw shell of a cooperating socket, a bulb rigid with said base and an element extending from the bulb 55 into the base beyond said joint, in combination with means mounted within said lamp base screw shell and projecting therefrom to engage a socket element and serving through its engagement with said socket element to disorganize said lamp element within the base and thus disable the lamp during the reverse rotation of the latter for withdrawal 60 from the socket.

5. An electric lamp having a screw shell 65 base for engagement with the screw shell of

a cooperating socket, a bulb rigid with said base and a lamp element extending therefrom into the base beyond said joint, in combination with means mounted within said lamp base screw shell and projecting therefrom to engage the socket screw shell, and serving through its engagement with said socket element to disorganize said lamp element within the base and thus disable the lamp during the reverse rotation of the latter 70 for withdrawal from the socket.

6. An electric lamp having a bulb and a base rigid therewith and affording a chamber beyond the joint between the bulb and base, in combination with lamp-disabling 80 means comprising a displaceable member arranged transversely within said chamber but projecting therefrom for operative detaining engagement with a lamp holder of standard 85 construction.

7. An electric lamp having a screw shell base with peripheral slot, a member mounted within said base and projecting through said slot for detaining engagement with an element of a socket of standard construction, 90 and a lamp element extending into said base and disorganized by said member incident to its angular displacement in said slot during the withdrawal of the lamp from the 95 socket, whereby the lamp is disabled.

8. An electric lamp having a screw shell base with peripheral slot, a member mounted within said base and projecting through said slot for detaining engagement with a socket element, said member being held 100 against displacement during the insertion of the lamp base into the socket, and means associated with said member for rendering the lamp inoperative incident to the angular displacement of said member in the slot during 105 the withdrawal of the lamp from the socket.

9. An electric lamp having a screw shell base with peripheral slot, a member mounted within said base and projecting through said slot for detaining engagement with a 110 socket element, said member being located at the following end of the slot during the insertion of the lamp base into the socket, and means associated with said member for rendering the lamp inoperative incident to 115 the angular displacement of said member in the slot during the withdrawal of the lamp from the socket.

10. An electric lamp having a chambered base, a swinging lever mounted within the chamber of the base but projecting therefrom for engagement with a socket element on the insertion of the lamp base in a holder, and means operated by the displacement of the lever during the withdrawal of the lamp 120 from its holder to disable the lamp.

11. An electric lamp having a chambered base, a swinging lever mounted within the chamber of the base but projecting from the base for engagement with a socket element 125

- on the insertion of the lamp in a holder, means preventing displacement of the lever during the insertion of the lamp in the holder but freeing said lever for movement 80
 8. on withdrawal of the lamp from the holder, and means operated by the displacement of the lever during the withdrawal of the lamp to disable the lamp.
12. An electric lamp having a screw shell 10 base, a lever mounted within the base but projecting therefrom at one end, said projecting end being shaped to afford a one-way engagement with a socket element, together with means within the base operated on by 15 the lever, on its detention incident to the reverse rotation of the lamp to remove the latter from the socket, to disable the lamp.
13. An electric lamp having a base, a bulb peripherally jointed above and to the base, 20 a portion of the bulb located axially inward of said joint and projecting into the base, and means operative within the base for rupturing said portion of the bulb to establish within the bulb lamp-disabling conditions. 25
14. An electric lamp having a base, a bulb cemented thereto, a sealed element serving on rupture to open a passage communicating with the interior of the bulb and projecting 30 from the inner end thereof into the lamp base, and means carried by and displaceable with respect to the base for rupturing said element.
15. An electric lamp having a bulb, a base 35 for securing the same in a lamp holder, a sealed element serving on rupture to open a passage communicating with the interior of the bulb and projecting from the inner end thereof into the lamp base, and displaceable 40 means automatically operative upon removal of the lamp from its holder, to rupture said element.
16. An electric lamp having a bulb, a hollow base, normally closed means within the 45 chamber of the base communicating with the interior of the bulb, and means associated with the base to open said normally closed means to establish lamp-disabling gaseous conditions within the bulb.
- 50 17. An electric lamp having a bulb, a single screw shell side contact rigidly secured to the bulb for rotation therewith in both directions, said screw shell being adapted to enter and directly engage a lamp holder of 55 standard construction, and displaceable means mounted within the lamp base but projecting therefrom to operatively engage a standard element of the lamp holder, together with a lamp element arranged within 60 the lamp base and disorganized by the movement of said displaceable means to disable the lamp during the rotation of the latter for withdrawal from the lamp holder.
- 65 18. An electric lamp having a bulb, a base secured thereto and adapted to enter a lamp 65 holder of standard construction, displaceable means arranged within the lamp base and adapted to operatively engage a standard element of the lamp holder on withdrawal of the lamp, together with a lamp element 70 within the base ruptured by the movement of said displaceable means to disable the lamp.
19. An electric lamp having a bulb, a base secured thereto and adapted to enter a lamp holder of standard construction, displaceable 75 means arranged within the lamp base and adapted to operatively engage a standard element of the lamp holder on withdrawal of the lamp, together with an element entering the lamp base from the bulb proper and displaced by said displaceable means, on operation of the latter, by the withdrawal movement of the base from the holder, to admit a lamp-disabling gas to the interior 80 of the bulb. 85
20. An electric lamp having a bulb, a base adapted to enter a lamp holder, a displaceable lamp-disabling means associated with the base but adapted for detaining engagement with an element of the lamp holder on withdrawal movement of the lamp therefrom, said disabling means moving with respect to the lamp base and out of operative engagement with the lamp holder after functioning, whereby the lamp and disabling 90 means may be freely withdrawn simultaneously from the lamp holder. 95
21. An electric lamp having a bulb, a base adapted to enter a lamp holder of standard construction, displaceable lamp-disabling 100 means arranged within the base but adapted for detaining engagement with an element of the lamp holder on withdrawal movement of the lamp therefrom, said disabling means moving into the base after functioning, 105 whereby the lamp and disabling means may be freely and simultaneously withdrawn from the lamp holder.
22. An electric lamp having a bulb, a base secured thereto and adapted to enter a lamp 110 holder, displaceable means associated with the base to engage an element of the lamp holder, and means operated by said movement of said displaceable means to admit lamp-disabling gas to the interior of the bulb 115 without injury to the joint between the bulb and base whereby the lamp may be withdrawn from the holder by grasping the bulb.
23. An electric lamp having a bulb, a base adapted to enter a lamp holder, displaceable 120 means associated with the base to engage an element of the lamp holder, and means operated by said movement of said displacement means to admit lamp-disabling gas to the interior of the bulb without injury to the latter, said displaceable means moving into the lamp base on functioning, to permit the free withdrawal of the base and disabling means from the lamp holder by grasping the bulb. 125
24. An electric lamp having a base, a bulb 130

having an exhaust tube extending into the base, and means associated with the base for rupturing said exhaust tube.

25. An electric lamp having a base, a bulb having an exhaust tube extending into the base, and means associated with the base for rupturing said exhaust tube, said means comprising a movable lever arranged within the base but projecting therefrom and shaped for detaining engagement with a lamp holder on the withdrawal movement of the lamp.

26. An electric lamp having a base, a bulb having an exhaust tube extending into the base, and means associated with the base for rupturing said exhaust tube, said means comprising a movable lever arranged within the base but projecting therefrom and shaped for detaining engagement with a lamp holder on the withdrawal movement of the lamp, together with means preventing operation of said lever during the insertion of the lamp base into its holder.

27. An electric lamp having a bulb, a base rigid therewith, and lamp-disabling means arranged within the base, but projecting

therefrom for operative detaining engagement with an element of an associated lamp holder of standard construction, said lamp-disabling means being automatically freed from detaining engagement with the holder after disabling the lamp so that the latter and the lamp-detaining means may be freely and simultaneously withdrawn from the holder.

28. As an assembly unit for a lamp base, a lever adapted to be positioned transversely within the base and having a plurality of supporting arms adapted to engage the base during assembly operation, certain of said arms being shaped for rupture within the base after assembly is completed.

29. An electric lamp having a base, a bulb having an exhaust tube entering the base, and a displaceable tube-rupturing lever projecting from the lamp base and having a one-way engagement with an element of a standard lamp holder.

In testimony whereof I have signed my name to this specification.

GILBERT W. GOODRIDGE.
